US00D666984S

(12) **United States Design Patent**
Suzuki

(10) **Patent No.:** **US D666,984 S**
(45) **Date of Patent:** **** Sep. 11, 2012**

(54) **MOBILE PHONE**

(75) Inventor: **Shigeaki Suzuki**, Tokyo (JP)

(73) Assignee: **Sony Ericsson Mobile Communications AB**, Lund (SE)

(**) Term: **14 Years**

(21) Appl. No.: **29/406,020**

(22) Filed: **Nov. 9, 2011**

(30) **Foreign Application Priority Data**

May 11, 2011 (EP) 1001862194-0001

(51) **LOC (9) Cl.** **14-03**

(52) **U.S. Cl.** ..... **D14/138 G**

(58) **Field of Classification Search** ..... D14/138 AD,
D14/138 G, 138 R, 138 AC, 138 C, 496,
D14/341, 345, 346, 203.7, 203.1, 203.3, 203.4,
